UNITED STATES PATENT OFFICE.

WILLIAM MEARS, OF CLEVELAND, OHIO, ASSIGNOR OF ONE-HALF TO MAUDE E. WILLIAMS AND ONE-HALF TO WILLIAM A. MEARS, OF CLEVELAND, OHIO.

SIGNAL SYSTEM.

937,837.

Specification of Letters Patent.

Patented Oct. 26, 1909.

Application filed November 27, 1907., Serial No. 404,128.

To all whom it may concern:

Be it known that I, WILLIAM MEARS, a citizen of the United States of America, residing at Cleveland, in the county of Cuyahoga and State of Ohio, have invented certain new and useful Improvements in Signal Systems; and I hereby declare the following to be a full, clear, and exact description of the invention, such as will enable others skilled in the art to which it pertains to make and use the same.

This invention relates to new and useful improvements in signal systems and particularly for use in connection with electric rail-
ways.

The object of this invention is to provide a block signal system for electric railways which can be cheaply constructed, which will be positive in operation and which, after being once installed, can be maintained without additional expense beyond the usual operating expense of the railway.

My invention, therefore, consists in the features of construction and combination of parts as described in the specification, pointed out in the claims and illustrated in the accompanying drawings.

In the accompanying drawings Figure 1 is a view of a portion of an electric railway system embodying my invention. Figs. 2 and 3 are enlarged detail views.

Again referring to the drawings 1 represents the rails of an electric railway of the usual construction and 2 indicates the poles which support the trolley wires 4 in the customary manner by means of an arm or bracket 5 secured to each pole. The trolley wires 4 are strung in the usual manner, which permits a certain amount of slack in the wire between each pair of holes. A conductor 7 which may be a wire much lighter and finer than the trolley wire is stretched between the poles immediately above the trolley wire and is spaced above the same a sufficient distance so that the two wires will not come in contact under normal conditions.

On the trolley wire 4 at suitable intervals are arranged contact devices, each of which comprises a small standard 8 which is soldered or otherwise secured to the trolley wire so as to be in electrical contact therewith. Each standard 8 is provided with a vertical central bore 9 in which is slidably arranged a small rod 10 which is preferably

provided with an enlarged head 11. The rod 10 is secured in the standard 8 by means of a screw 12 which permits it to be adjusted up and down in said standard. A yoke 14 which is preferably provided with a covering of some insulating material 13 is arranged to straddle the conductor 7 and the ends of this yoke are secured by means of screws 16 in lugs 15 formed on the standard 8. This yoke by thus straddling the conductor 7 serves as a guide and holds the standard 8 vertical so that the head of the rod 10 will always be in position to come in contact with the conductor 7 when the trolley wire is raised up and brought closer to the conductor.

In the drawings 17 represents a trolley car of the usual construction which is provided with a trolley pole 18 carrying a trolley wheel 19 which is held against the trolley wire 4 by a spring 20 which supports the pole in the usual manner.

The signal circuit is indicated by *a* and one terminal thereof is connected to ground or to a rail and the other terminal thereof is connected with the conductor 7. In the signal circuit is arranged a lamp *b* or any other suitable signaling device.

The operation of the signal system is as follows. The conductor 7 is supported between the poles as before explained, directly above the trolley wire and as there is always a certain amount of slack in the trolley wire therefore as the trolley car passes beneath the trolley wire the trolley wheel will be pressed up against the trolley wire by the springs which support the trolley pole and therefore the trolley wire will be lifted and brought closer to the conductor 7. Now the distance between the trolley wire and the conductor will of course vary at different points between the supporting poles, for instance the portion of the trolley wire centrally between the supporting poles will be lifted higher and will come closer to the conductor than the portion of the trolley wire nearer the supporting poles and therefore the contact devices are adjusted accordingly by lowering or raising the rods 10. When the trolley wire is lifted by the passage of a car the contact devices on the trolley wires are brought into contact with the conductor 7, thereby closing the signal circuit and giving the required signal.

What I claim is;

1. In a signal system for electric railways, in combination with a trolley wire, a conductor supported longitudinally of said trolley wire and above and in proximity thereto, contact devices arranged on said trolley wire, guides extending upwardly on each side of said conductor so that the latter will be held in alinement with said contact devices and said contact devices will engage the conductor when the trolley wire is raised by an upward pressure of the trolley of a passing car.
2. In a signal system for electric railways, in combination with a trolley wire, a signal wire supported above and in proximity thereto, said signal wire extending longitudinally of said trolley wire, contact devices carried by one of said wires, and adapted to be engaged by the other when the trolley wire is raised by the trolley of a passing car, and an electric signal connected to said signal wire.
3. In a signal system for electric railways, the combination with a trolley wire of a conductor supported above and in proximity

thereto, a series of standards on said trolley wire, rods adjustably mounted in said standards, yokes arranged over said conductor and secured to said standards, and an electric circuit having one terminal connected 30 with said conductor and a signaling device arranged in said electric circuit.

4. In a signal system for electric railways, the combination with a trolley wire of a conductor supported above and in proximity 35 thereto and adjustable contact devices so arranged on said trolley wire that when a trolley wheel passes beneath the said trolley wire and in contact therewith it will bring the trolley wire into contact with said conductor, an electric circuit having one terminal connected with said conductor and a signaling device arranged in said circuit.

In testimony whereof, I sign the foregoing specification, in the presence of two wit- 45 nesses.

WILLIAM MEARS.
